UNITED STATES PATENT OFFICE.

CHARLES T. HATCH, OF ALBION, MICHIGAN, ASSIGNOR TO UNION STEEL PRODUCTS COMPANY, OF ALBION, MICHIGAN.

VENDING RACK OR STAND.

Application filed November 3, 1925. Serial No. 66,509.

My improved vending rack is especially designed by me for holding receptacle carriers for lubricant and the like such as employed at filling stations and I have illustrated my improvements as embodied for that purpose. My improvements are, however, adapted for other purposes as in the display of merchandise in grocery stores and the like.

10 The objects of the invention are:

First, to provide an improved collapsible stand or rack which may be readily collapsed for shipment or storage and easily set up by the user.

15 Second, to provide a rack which may be made of comparatively light material and at the same time is very strong and rigid when erected.

20 Objects pertaining to details and economies of my invention will definitely appear from the detailed description to follow. The invention is clearly defined and pointed out in the claims.

25 A structure embodying the features of my invention is clearly illustrated in the accompanying drawing forming a part of this application, in which:

30 Fig. 1 is a perspective view of a stand or rack embodying the features of my invention, one of the end shelves being omitted for convenience in illustration.

35 Fig. 2 is a fragmentary side elevation, two bottle or receptacle carriers being arranged upon the stand.

Fig. 3 is a fragmentary perspective view 35 showing structural details.

Fig. 4 is a perspective view of the rack of Fig. 1 collapsed for shipment or storage.

40 My improved stand or rack comprises a rectangular main top frame 1 formed of angle iron and disposed with the angles facing inwardly. The angle iron legs 2 are arranged facing inwardly and the transversely disposed arms of the legs are cut away at 45 their upper ends as at 3, providing upwardly projecting ears 4 which are secured by the pivots 5 to the longitudinal or side members of the main frame 1.

45 I provide an auxiliary top frame 6 which is also rectangular and formed of angle iron disposed with the angles facing upwardly. This main top frame is supported by pairs of links 7 secured to the side members of the main top frame by the pivots 8. These links 55 are detachably secured to the side or longi-

tudinal members of the main top frame by the bolts 9.

The legs are connected by the cross pieces 10 and are braced by braces 11 and 12 which are pivotally secured to the legs by the pivots 13 and detachably to the frame 1 by the bolts 9. The braces 12 are extended and secured to the auxiliary top frame 6 by means of the pivots 14.

Bottom slats 15 are arranged on the main top frame at each side of the auxiliary top frame, providing supports for the carriers 16 or other article to be supported or displayed. The auxiliary top frame has slats 17 so that it constitutes a support for such an article as the carrier 16.

50 A shelf may be provided at one or both ends comprising a U-shaped angle iron frame 18, the arms of the frame being pivotally and detachably secured to the legs by the bolts 19. The shelf is supported in its erected position by the braces 20 which are engaged with the pivots 13. By removing the bolts 19 the shelf may be collapsed against the legs. By disengaging the bolts 9 the legs may be collapsed and also the links for the auxiliary top; thereby permitting the compact collapsing of the parts as shown in Fig. 4, the parts all, however, remaining connected as a unit and being handled as such.

55 I have illustrated and described my improved stand or rack as embodied by me for use in supporting bottle or can dispensing carriers. It may be used for various uses without modification and it is readily adaptable for particular requirements.

Having thus described my invention what I claim as new and desire to secure by Letters Patent is:

60 1. In a collapsible stand or rack, the combination of a rectangular angle iron main top frame disposed with the angles facing upwardly, angle iron legs disposed with their angles facing inwardly and having their transversely disposed arms cut away at their 65 upper ends providing projecting pivot ears, said ears being pivoted to the longitudinal members of said top frame, a rectangular angle iron auxiliary top frame disposed with the angles facing upwardly, supporting links therefor pivotally connected to the side members of said auxiliary top frame, bolts detachably connecting said supporting links to the side members of said main top frame, 70 braces pivotally connected to the legs and 75

detachably secured to said main top frame by said bolts, one pair of said braces being extended and pivotally secured to the side members of said auxiliary top frame constituting braces therefor, bottom slats disposed on said main top frame on each side of said auxiliary top supporting links, a shelf comprising a U-shaped angle iron frame disposed with its angles facing upwardly, the arms of said shelf frame being detachably connected to one pair of said legs to collapse against the same, and braces for supporting said shelf in erected position pivotally engaged with the leg brace attaching pivots.

2. In a collapsible stand or rack, the combination of a rectangular angle iron main top frame disposed with the angles facing upwardly, angle iron legs disposed with their angles facing inwardly and having their transversely disposed arms cut away at their upper ends providing projecting pivot ears, said ears being pivoted to the longitudinal members of said top frame, a rectangular angle iron auxiliary top frame disposed with the angles facing upwardly, supporting links therefor pivotally connected to the side members of said auxiliary top frame, bolts detachably connecting said supporting links to the side members of said main top frame, braces pivotally connected to the legs and detachably secured to said main top frame by said bolts, one pair of braces being extended and pivotally secured to the side members of said auxiliary top frame constituting braces therefor, and bottom slats disposed on said main top frame on each side of said auxiliary top supporting links.

3. In a collapsible stand or rack, the combination of a rectangular main top frame, legs pivoted to the longitudinal members of said top frame, a rectangular auxiliary top frame, supporting links therefor pivotally connected to the side members of said auxiliary top frame, bolts detachably connecting said supporting links to the side members of said main top frame, braces pivotally connected to the legs and detachably secured to said main top frame by said bolts, one pair of said braces being extended and pivotally secured to the side members of said auxiliary top frame constituting braces therefor, a shelf comprising a U-shaped frame, the arms of said shelf frame being detachably connected to one pair of said legs

to collapse against the same, and braces for supporting said shelf in erected position pivotally engaged with the leg brace attaching pivots.

4. In a collapsible stand or rack, the combination of a rectangular main top frame, legs pivoted to the longitudinal members of said top frame, a rectangular auxiliary top frame, supporting links therefor pivotally connected to the side members of said auxiliary top frame, bolts detachably connecting said supporting links to the side members of said main top frame, and braces pivotally connected to the legs and detachably secured to said main top frame by said bolts, one pair of said braces being extended and pivotally secured to the side members of said auxiliary top frame constituting braces therefor.

5. In a collapsible stand or rack, the combination of a rectangular main top frame, supporting legs therefor, a rectangular auxiliary top frame, supporting links therefor, bolts connecting said supporting links to the side members of said main top frame, braces pivotally connected to the legs and secured to said main top frame by said bolts, one pair of said braces being extended and secured to the side members of said auxiliary top frame constituting braces therefor, bottom slats disposed on said main top frame on each side of said auxiliary top supporting links, a shelf comprising a U-shaped frame, the arms of said shelf frame being detachably connected to one pair of said legs, and braces for supporting said shelf in erected position engaged with the leg brace attaching pivots.

6. In a collapsible stand or rack, the combination of a rectangular main top frame, supporting legs therefor, a rectangular auxiliary top frame, supporting links therefor, bolts connecting said supporting links to the side members of said main top frame, braces connected to the legs and secured to said main top frame by said bolts, one pair of said braces being extended and secured to the side members of said auxiliary top frame constituting braces therefor, and bottom slats disposed on said main top frame on each side of said auxiliary top supporting links.

In witness whereof I have hereunto set my hand.

CHARLES T. HATCH.
